CLAIM

The ornamental design for a press body for use in extended nip presses for paper making as shown and described.

DESCRIPTION

1. Press body for use in extended nip presses for paper making

1.1 : Perspective

1.2 : Front

1.3 : Back

1.4 : Right

1.5 : Left

1.6 : Top

1.7 : Bottom

The characteristic features of the design lie in the shape of the press body for use in extended nip presses for paper making as shown; The design relates to a press body for use in extended nip presses for paper making.
